SAFETY RAZOR

Carl Heinrich Heinlein, Sheffield, England

Application June 1, 1936, Serial No. 83,001
In Great Britain June 8, 1935

17 Claims. (Cl. 30—74.1)

This invention relates to safety razors and has for its main object to provide an improved construction having a minimum of separate parts and simple to operate.

5 A further object is the provision of a safety razor comprising only two parts which are normally separable, namely the blade and the blade holder or frame. A further object of the invention is the provision of a safety razor having an 10 apertured blade which is placed in position upon the holder or frame by passing the handle of the latter through the aperture of the blade.

15 Other objects and advantages of the invention will be fully appreciated from the following description.

According to the present invention a safety razor comprises a blade base having a guard, a handle permanently attached to the base, clamping means at the handle side of the base for clamping a blade against the base and a blade 20 apertured to pass freely over the length of the handle and over the clamping means into contact with the base. Thus the safety razor comprises only two normally separable units, namely 25 the frame (which incorporates the base, guard, clamping means and handle) and the blade.

The base and guard of the razor are preferably formed by a unitary structure and are preferably integral with one another. In this construction the guard may be separated from the base by a slot at least as long as the blade edge, through which slot the blade projects so that its edge lies on the side of the unitary base and guard opposite to that on which the main body 35 of the blade lies.

The guard may be off-set from the base to provide the desired amount of shaving clearances. Two guards may be provided, to co-operate with the two cutting edges of a double edged blade, situated respectively at opposite sides of the base and separated therefrom by slots of different widths or off-set therefrom by different amounts to provide two different shaving clearances.

40 Preferably the guard and base are curved or hollowed on the handle side so as to flex a blade of the thin wafer type when clamped in position on the base.

In a convenient construction the handle is rotatable relative to the base and rotation of the handle operates the clamping means. The clamping means may take various forms. For example it may comprise a rotatable interrupted or otherwise non-circular collar or face cam co-axial with the handle and adapted to pass through the 45 aperture of the blade and when rotated relative

thereto, to engage the blade and urge it towards the base. If desired the interrupted collar or face cam may be movable axially as well as being rotatable. In this case it may have a quick-pitch screw engagement with a stem secured to the base and carrying the handle and may be connected to the handle for axial movement thereby so that such axial movement of the handle and the interrupted collar or face cam causes rotation of the latter. The pitch of 10 the quick-pitch screw engagement need not be uniform and in one preferred construction the pitch is substantially infinite at the approach of the interrupted collar or face cam towards the base, so that the final clamping movement of the 15 interrupted collar or face cam takes place substantially without rotation. The handle may have screw engagement with the stem and may abut against or may be rotatably connected to the interrupted collar or face cam so as to move 20 the latter to the clamping position. Alternatively the handle may have a pin and slot or equivalent connection with the stem allowing axial movement of the handle without rotation for the major part of the permitted travel and rotational movement with or without axial movement at the 25 clamping end of the travel.

An alternative form of clamping means may comprise one or more clamping lugs each pivoted about an axis at right angles to the handle. 30 Each of the clamping lugs may be connected by a link to a yoke which is movable axially of the handle for example by means of a screw. Alternatively each of the clamping lugs may be provided with a toothed sector concentric with its 35 pivotal axis and engaged by a co-operating part adapted to be moved by the handle or by a movable part of the handle. For example the co-operating part may be a screw or worm engaging the toothed sector and adapted to be rotated 40 by means of the handle or by means of a rotatable part of the handle, or the co-operating part may comprise a rack engaging the toothed sectors and adapted to be moved axially of the handle. 45

Certain forms of safety razor are shown by way of example in the accompanying drawings in which:—

Figure 1 is a part elevation and part section of one form of safety razor: 50

Figure 2 is an inverted plan of Figure 1, the handle being shown in section:

Figure 3 is a part elevation and part section of another form of safety razor: 55

Figure 4 is an inverted plan view of Figure 3, partly in section, on the line 4-4 thereof:

Figure 5 is a view partly in section but mainly in elevation, similar to Figure 3, showing the 5 parts in a different position:

Figure 6 is a part elevation and part section of another form of safety razor:

Figure 7 is a side elevation of Figure 6: and

Figure 8 is a part elevation and part section 10 of yet another form of safety razor.

Referring now to Figures 1 and 2, the razor frame comprises a blade base 10, and two opposite guards 11 separated from the blade base 10 by slots 13 and connected to the base 10 by 15 bridges 14. A unitary handle 15 is rotatably secured to the base 10, for example by a spigot 16 passed through a counter-sunk hole in the base 10 and riveted. The blade clamping means is formed integrally with the handle 15 and comprises 20 an interrupted or non-circular collar or face cam 17 of which the corresponding surfaces 18 facing the base 10 are bevelled or helical. The base 10 is provided with locating pegs 19 for locating a blade 20 thereon.

25 The blade 20 is of the thin flexible or wafer type and is provided with an aperture 21 of a configuration similar to that of the interrupted collar or face cam 17 and of sufficient dimensions to pass clearly over the handle 15 and over 30 the collar or face cam 17. The blade 20 is also provided with perforations adapted to engage the locating pegs 19 and these perforations may, if desired, be extensions of the aperture 21.

In the arrangement shown in Figures 1 and 2, 35 the base 10 and guards 11 are preferably curved as shown into a hollow form similar to that shown in Figure 7. However, if desired the bridges 14 may be cranked to off-set the guards 11 from the base 10, thus to provide the necessary shaving clearance and, when the bridges 40 14 are so off-set, the base 10 may, if desired, be flat or of small curvature. Furthermore the slots 13 may be of different widths or the bridges 14 on opposite sides of the base 10 may be differently 45 cranked to provide different shaving clearances for the two sides of the razor.

In the operation of the razor, the handle 15 is threaded through the aperture 21 of the blade and the blade is passed along the handle 15 50 until it is in contact near its edges with the base 10. The handle 15 is then rotated so that the bevelled or helical faces 18 of the interrupted collar or face cam 17 engage the edges of the aperture 21 of the blade 20. When the 55 handle is further rotated, the inclined surfaces 18 urge the blade towards the base 10 thereby flexing it until, when the interrupted collar or face cam 17 assumes the position shown in chain lines in Figure 2, the blade is fully flexed and 60 securely clamped against the base 10 with its edges projecting through the slots 13 on the side of the base 10 and guards 11 opposite to that from which the handle 15 projects.

In order to release the blade, the handle 15 65 is rotated in the reverse direction until the interrupted collar or face cam 17 assumes the position shown in full lines in Figures 1 and 2, when the blade can be passed over the interrupted collar or face cam 17 along the handle 70 15 and removed.

In the arrangement shown in Figures 3, 4 and 5 the handle 15 is hollow or tubular and is rotatable and axially movable upon a stem 22. The stem 22 is rigidly secured to the base 10 by 75 being screwed and soldered thereto.

The interrupted collar or face cam 17 is carried upon a bush 23 which is slidable and rotatable upon the stem 22. The stem 22, however, is provided with a groove 24 which, at its end near the base 10, is parallel with the axis of 5 the stem 22 and of the handle 15 but has a helical portion 25 extending around the stem 22 somewhat more remote from the base 10. A pin 26 in the bush 23 engages the groove 24. The handle 15 is provided with a slot having a 10 portion 27 extending parallel to its axis and a helical portion 28. A pin 29 secured to the stem 22 engages this slot. The handle 15 is connected to the bush 23 for the transmission of axial movement by means of a pin 30 extending 15 through the bush 23 and engaging a circumferential groove 31 formed in the handle.

In the operation of the razor shown in Figures 3, 4 and 5, before insertion of the blade, the parts are initially in the position shown in Figure 5. The handle 15 is threaded through the aperture 21 of the blade 20 and the blade is passed into contact with the base. The handle 15 is then pushed axially towards the base 10 thus urging the bush 23 axially towards the 25 base 10. The bush 23 is caused to rotate by engagement of the pin 26 with the helical part 25 of the slot 24. Such rotation of the bush causes the interrupted collar 17 to over-lie portions of the blade 20 as shown in Figure 4. 30 Simultaneously with the assumption by the interrupted collar 17 of the position shown in Figure 4 the pin 26 enters the axial portion of the groove 24 and the pin 29 reaches the junction of the axial slot 27 with the helical slot 28 35 of the handle 15. The handle 15 is then rotated so as to urge it and consequently the bush 23 and interrupted collar 17 axially and thus to apply the final clamping pressure to the blade. No rotation of the bush 23 and interrupted collar 40 17 takes place during this final movement, since the pitch of the screw connection provided by the groove 24 and pin 26 is here infinite.

The pitch of the helical slot 28 is preferably 45 small in order to enable adequate clamping force to be applied to the blade 20 and also to secure irreversibility and thus to prevent the clamping pressure being relieved while the razor is in normal use.

In order to remove the blade 20, the handle 15 50 is slightly rotated to bring the pin 29 into the axial slot 27 of the handle 15 and the handle is pulled away from the base 10, the pin 26 travelling along the groove 24, 25 and thus causing the parts to assume the position shown in Figure 5, after 55 which the blade may be removed over the interrupted collar 17 and handle 15.

Referring now to Figures 6 and 7, the handle 15 is secured permanently by a slotted bracket 32 to the base 10. Two clamping lugs 33 are respectively pivoted about axes at right angles to the handle upon pins 34 extending through the bracket 32. A yoke 35 slides in a slot 36 formed in the handle 15 and the clamping lugs 33 are respectively connected by links 37 to this yoke. 60 The yoke 35 is rotatably connected to a spindle 38 having a screw connection 39 with the hollow handle 15. The spindle 38 is preferably hollow and is provided with an external knurled operating knob 40.

In the operation of the razor shown in Figures 6 and 7, in order to insert the blade, the knob 40 is rotated to retract the yoke 35 to the position indicated in chain lines on the right-hand side of Figure 6 thus moving, by means of the links 37. 75

the clamping lugs 33 into the position shown in the chain lines. The handle 15 is threaded through the aperture of the blade and the blade is passed into contact with the base 10, the aperture being sufficiently large to pass over the clamping lugs 33 when these are in the position shown in chain lines. The operating knob 40 is then rotated to move the parts so that the clamping lugs 33 assume the position shown in full lines 10 in Figure 6, thus clamping the blade securely against the base 10. In order to remove the blade reverse sequence of these operations is carried out.

In the arrangement shown in Figure 8, the 15 clamping lugs 33 are provided with toothed sectors 41. The toothed sectors 41 engage a worm 42 formed upon the end of a spindle 43 which is rotatable within the hollow handle 15 and secured against axial motion by a pin 44 which engages 20 a circumferential groove in the stem 43. The stem 43 is provided with an external operating knob 40.

The manner of operation of the safety razor shown in Figure 8 is substantially similar to that 25 of the safety razor shown in Figures 6 and 7, the rotation of the worm 42 by the knob 40 retracting the clamping lugs 33 into the position shown in chain lines on the right-hand side of Figure 8.

30 Instead of engaging a worm 42, each toothed sector 41 might engage racks movable axially in the handle and operated in a manner similar to the yoke 32 shown in Figure 6.

It will be appreciated that certain embodiments of safety razor in accordance with the invention have been described with reference to and shown in the accompanying drawings by way of example only and that many modifications may be made without departing from the scope 40 of the invention.

What I claim is:

1. A safety razor comprising a blade-base having a guard, a handle permanently attached to the blade-base, clamping means at the handle 45 side of the base for clamping a blade against the base and a blade apertured to pass freely over the length of the handle and over the clamping means into contact with the blade-base.

2. A safety razor comprising a blade-base, two 50 guards respectively disposed at opposite sides of the blade-base and separated therefrom by slots, the two guards being differently related to the proximate sides of the blade-base to provide two different shaving clearances, a handle permanently attached to the blade-base, clamping means at the handle side of the blade-base for clamping a blade against the blade-base, and a two-edged blade apertured to pass freely over the length of the handle and over the clamping 55 means into contact with the blade-base.

3. A safety razor comprising a blade-base having a guard, a handle rotatably secured to the blade-base, clamping means at the handle side of the blade-base for clamping a blade against the blade-base, a blade apertured to pass freely over the length of the handle and over the clamping 60 means into contact with the blade-base and an operative connection between the rotatable handle and the clamping means for operation of the clamping means by rotation of the handle.

4. A safety razor comprising a blade-base having a guard, a handle permanently attached to the blade-base, clamping means comprising a rotatable non-circular member disposed at the 65 handle side of the blade-base for clamping a blade

against the blade-base, means for rotating said non-circular member, and a blade having a non-circular aperture adapted to pass freely over the length of the handle and over the clamping means into contact with the blade-base. 5

5. A safety razor comprising a blade-base having a guard, a handle permanently attached to the blade-base, clamping means comprising a rotatable non-circular member provided with cam faces disposed at the handle side of the 10 blade-base for clamping a blade against the blade-base, means for rotating said non-circular member, and a blade having a non-circular aperture adapted to pass freely over the length of the handle and over the clamping means into contact with the blade-base. 15

6. A safety razor comprising a blade-base having a guard, a handle rotatably secured to the blade-base, an interrupted face cam integral with the handle and adjacent to the blade-base for 20 clamping a blade against the blade-base and a blade having a non-circular aperture adapted to pass freely over the length of the handle and over the interrupted face cam to be engaged and clamped thereby into contact with the base. 25

7. A safety razor comprising a blade-base having a guard, a handle permanently attached to the blade-base, clamping means comprising a rotatable and axially movable non-circular member disposed at the handle side of the blade-base for 30 clamping a blade against the blade-base, means for imparting rotation and axial movement to said non-circular member, and a blade having a non-circular aperture adapted to pass freely over the length of the handle and over the clamping 35 means into contact with the blade-base.

8. A safety razor comprising a blade-base having a guard, a stem secured to the blade-base, clamping means comprising a non-circular member having a quick-pitched screw engagement 40 with the stem, a handle mounted upon said stem for axial movement thereon, an operative connection between said handle and said non-circular member for imparting thereto axial movement along said stem to cause rotational movement of the non-circular member, and a blade having a non-circular aperture adapted to pass freely over the length of the handle and over the clamping 45 means into contact with the blade-base.

9. A safety razor comprising a blade-base having a guard, a stem secured to the blade-base, clamping means comprising a non-circular member having a screw engagement with the stem, the pitch of said screw engagement being substantially infinite at the approach of the non-circular member towards the blade-base, a handle slidably mounted upon the stem for axial movement thereon, an operative connection between said handle and said non-circular member for imparting thereto axial movement along said 50 stem, and a blade having a non-circular aperture adapted to pass freely over the length of the handle and over the clamping means into contact with the blade-base. 55

10. A safety razor comprising a blade-base having a guard, a stem secured to the blade-base, clamping means comprising a non-circular member having a screw engagement with the stem, the pitch of said screw engagement being substantially infinite at the approach of the non-circular member towards the base, a handle slidably mounted upon the stem for axial movement thereon, an operative connection between the handle and the stem adapted to permit limited axial movement of the handle relative to the 70 75

- stem without rotation over the major portion of the permitted travel of the handle and to cause rotational movement of the handle relative to the stem near one end of the permitted travel, 5 an operative connection between said handle and said non-circular member for imparting thereto axial movement along said stem, and a blade having a non-circular aperture adapted to pass freely over the length of the handle and over the 10 clamping means into contact with the blade-base.
11. A safety razor comprising a blade-base having a guard, a handle permanently attached to the blade-base, a clamping lug pivoted about an axis at right angles to the handle, means for 15 rotating the clamping lug about its axis to and from a clamping position, and a blade apertured to pass freely over the length of the handle and over the clamping lug into contact with the blade-base.
12. A safety razor comprising a blade-base having a guard, a handle permanently attached to the blade-base, a clamping lug pivoted about an axis at right angles to the handle, a yoke 20 movable axially of the handle, a link connecting the yoke to the clamping lug, screw means for moving the yoke along the handle, and a blade apertured to pass freely over the length of the handle and over the clamping lug into contact with the blade-base.
13. A safety razor comprising a blade-base having a guard, a handle permanently attached to the blade-base, a clamping lug pivoted about an axis at right angles to the handle, a toothed 25 sector upon the clamping lug and concentric with its pivotal axis, means engaging the toothed sector for rotating the lug about its axis, and a blade apertured to pass freely over the length of the handle and over the clamping lug into contact with the blade-base.
14. A safety razor comprising a blade-base having a guard, a handle permanently attached to the blade-base, a clamping lug pivoted about an axis at right angles to the handle, a toothed sector upon the clamping lug and concentric with 30 its pivotal axis, a worm rotatably associated with the handle and engaging the toothed sector, means for rotating the worm, and a blade aper- 35 tured to pass freely over the length of the handle and over the clamping lug into contact with the blade-base.
15. A safety razor comprising a blade-base having a guard, a handle permanently attached to the blade-base, a clamping lug pivoted about an axis at right angles to the handle, a toothed sector upon the clamping lug and concentric with its pivotal axis, a rack movable axially of the handle and engaging the toothed sector, means for moving the rack, and a blade apertured to pass freely over the length of the handle and over the clamping lug into contact with the blade-base. 5
16. A safety razor comprising a combined cap and guard member, a handle including a part fixed to said member and a part rotatably carried thereby, a blade having an opening to receive the handle when the blade is dropped thereover, and means carried by the rotatable part of 10 the handle and cooperating with the blade when the same is turned relative to the combined cap and guard member for locking the blade in position. 15
17. A safety razor comprising, in combination, a combined cap and guard member having a central stem fixed thereto and carrying oppositely disposed guard bars and blade guiding means, a handle rotatably mounted on said stem end carrying oppositely disposed arms adapted in one 20 position to extend generally longitudinally of the combined cap and guard member and in the other position to extend generally transversely thereof, a blade having a central cut-out section of a form adapted to pass over the handle 25 and said arms when the latter are disposed longitudinally of said member, said blade being formed so as to cooperate with the blade guiding means on said combined cap and guard member so that the blade is guided into proper position 30 on the combined cap and guard member when the blade is passed over the handle and arms, rotation of the handle moving said arms to their transverse position in which they bear against said blade and hold the same firmly in shaving 35 position. 40
- CARL HEINRICH HEINLEIN.
